F. G. Fischer,

ATTORNEY,

UNITED STATES PATENT OFFICE

GLEN O'BRIEN, OF TROY, KANSAS; C. M. O'BRIEN EXECUTRIX OF SAID GLEN O'BRIEN,
DECEASED

PORTABLE COOLING APPARATUS

Application filed February 5, 1932. Serial No. 591,104.

My invention relates to an air-conditioning apparatus and includes means for cooling and washing the air, and means for distributing the conditioned air throughout the 5 room in which the apparatus is located.

Cooling of the air is effected by a suitable liquid such as water which is reduced to the 10 desired temperature by contact with a suitable cooling agent preferably in the form of ice down which the water flows to the bottom of a tank containing the ice. The cooled water is then pumped upwardly from the tank and through a radiator from which it is discharged and after taking up heat from the 15 air is recooled by again contacting with the ice.

The radiator, which is located in the upper part of the apparatus, has cooling tubes arranged in staggered relation to each other 20 so that the air will contact with each, and the water is discharged more in the form of rain than spray so the air can not pass therethrough without becoming thoroughly washed.

25 A silencer is provided to break the fall of the water and thus reduce to a minimum the noise which would otherwise occur if the water were permitted to fall directly upon the ice.

30 The invention also contemplates the employment of regulating means for controlling the circulation of the water so that meltage of the ice by the water flowing thereover may be reduced to a minimum during moderate 35 temperatures.

While it is not my intension to limit the use of the apparatus to any particular place it will be found especially useful in conditioning the air in hospital wards, restaurants, 40 barber shops, beauty parlors, offices and other places where cooling, washing and dehumidizing of the air is especially desirable.

In order that the invention may be fully 45 understood, reference will now be made to the accompanying drawings, in which:

Fig. 1 is a perspective view of the apparatus.

Fig. 2 is a broken perspective partly in 50 section of the radiator forming an important feature of the invention.

Fig. 3 is a vertical section of the apparatus on line 3—3 of Fig. 1.

Fig. 4 is a broken vertical section on line 4—4 of Fig. 3 with the cake of ice shown in latter figure removed.

Fig. 5 is a broken sectional view on line 5—5 of Fig. 6.

Fig. 6 is a broken cross section on line 6—6 of Fig. 5.

In carrying out the invention I employ a 60 cabinet 2 consisting of top and bottom walls 4 and 6, front and rear walls 8 and 10 and side walls 12. The cabinet 2 may be made in different sizes according to the capacity 65 desired and when made in portable sizes is mounted upon casters 14, to facilitate removal from one room to another.

16 designates a receptacle or tank which 70 occupies the major portion of the cabinet 2 and is preferably of a size to hold a standard cake of ice to be used for cooling purposes. The ice is introduced into the tank 16 through an opening normally closed by a lid 18 hingedly connected to the top wall 4 of the cabinet. The four sides and bottom of the 75 tank 16 are covered with suitable insulation 17 to conserve the ice therein.

20 designates a radiator supported by brackets 21 in an air passage 22 extending 80 through the upper portion of the cabinet 2 and provided with an inlet 24 and an outlet 26. The inlet 24 is protected by an open mesh screen 25.

The radiator 20 consists of a lower chamber 28, an upper chamber 30 and vertically 85 disposed tubes 32 connecting said chambers. The tubes 32 are arranged in staggered relation as best shown in Fig. 5, so that all of the air passing through the passage 22 will come into contact with said tubes. The foregoing arrangement of the tubes 32 also prevents water discharged from the upper rear portion of the radiator from being carried to the outlet 26 by the air current flowing through the passage 22. The lower chamber 90 28 of the radiator is divided into two compartments by a partition 34 having perforations 36 to insure equal flow of the cooling fluid through all of the tubes 32. The upper chamber 30 of the radiator projects rearward- 95

ly of the lower chamber 28 as shown by Figs. 2 and 3, in order to discharge the cooling liquid back into the tank 16 through perforations 38 in the bottom of said rearward projection. In order to enhance the efficiency of the radiator 20 the tubes 32 are equipped with a plurality of horizontally disposed fins 40.

The cooling liquid consists preferably of 10 meltage from the ice within the tank 16, or water placed within said tank, and is pumped to the radiator 20 by suitable means such as a centrifugal pump 42 having its inlet connected to the lower portion of the tank 16 15 by a pipe 44 and its outlet connected to a discharge pipe 46 communicating with the lower portion of the radiator chamber 28. The pipe 46 is equipped with a valve 48 for regulating the flow of the cooling liquid to the 20 radiator 20. Said pipe 46 is also equipped with a short discharge pipe 50 to which a hose may be connected for conducting the water from the cabinet 2 when it is desired to drain the tank 16. During the draining operation 25 the valve 48 of course will be closed while a valve 52 on the pipe 50 will be opened.

The pump 42 is operated by suitable means such as an electric motor 54, which, together with the pump is located in the lower front 20 portion of the cabinet 2, so that access may be readily had thereto for inspection or repairs by opening a door 56 hinged to the front wall 8 of the cabinet.

Air is circulated through the passage 22 35 by suitable means such as a fan 58 located in the outlet 26 and driven by suitable means such as an electric motor 60.

In apparatus of this character it is important to reduce the noise of operation to a minimum, especially when the apparatus is used in a hospital, or sick room, so in order to eliminate, or at least greatly reduce the noise which would otherwise occur if the water discharged from the radiator were permitted 45 to fall directly into the tank 16, I intercept the fall by means of a silencer 62 constructed preferably in the form of an open mesh screen 64 and arranged at an incline as best shown by Figs. 3 and 4. The lower longitudinal 50 portion of the silencer 62 rests upon the upper edge of the tank 16, while the upper longitudinal portion of said silencer is hingedly connected to the sides of a trough 66, so that the silencer may be swung upwardly against 55 the fins 40 and thus be out of the way when the tank 16 is being supplied with ice.

The trough 66 surrounds the front and side walls of the lower chamber 28 to catch any condensation from the radiator 20 and conduct it into the tank 16. Any other condensation not caught by the trough 16 is collected in a drip pan 68 covering the bottom wall 6 of the cabinet 2 and provided with a valve-controlled drain pipe 70.

65 With the parts arranged as shown and de-

scribed it is apparent that when the cooling water from the tank 16 is pumped upwardly through the radiator 20 and discharged from the perforations 38 it will not only cool, but will also wash the air circulated through the passageway 22 by the fan 58. As the water is discharged from the perforations 38 it falls upon the silencer 62 and then flows downwardly over the ice whereby it is recooled preparatory to again being circulated through the radiator 20. The temperature of the air is initially reduced as it flows over the open upper end of the tank 16 by the ice within said tank, so that the radiator 20 will be more effective in imparting a lower temperature to the precooled air. As it is desirable to operate a machine of this character as economically as possible it is important to be able to regulate the circulation of the cooling water and thus economize in the use of ice. This is accomplished by providing the pipe 46 with the valve 48 which may be left open to its full capacity when it is desired to obtain maximum cooling during high temperatures, or partially closed to reduce the circulation of the water during moderate temperatures of the outer atmosphere.

From the foregoing description it is apparent that I have provided an efficient apparatus which is well adapted for the purpose intended, and while I have shown one form of the invention I reserve all rights to such other forms and modifications thereof as properly fall within the spirit and scope of the invention as claimed.

Having thus described my invention, what I claim and desire to secure by Letters Patent, is:

1. An apparatus of the character described comprising a cabinet having an air passage extending therethrough, means for circulating air through said passage, a radiator arranged within said passage and having a chamber with a multiplicity of perforations adapted to discharge a cooling liquid upon the air, means within the cabinet for cooling said liquid, and means for circulating the liquid from said cooling means through said radiator.

2. An apparatus of the character described comprising a cabinet having an air passage extending therethrough, radiator tubes arranged within said passage, lower and upper radiator chambers connected to said tubes, a perforated partition within the lower chamber, perforations in the upper chamber through which a cooling liquid is discharged, means for receiving and cooling said liquid, and a pump for pumping the liquid from the receiving means to the lower chamber of the radiator.

3. An apparatus of the character described comprising a cabinet having an air passage extending therethrough, vertically disposed radiator tubes arranged in staggered relation

to each other within said passage, lower and upper radiator chambers connected to said tubes, said upper chamber having a projection with perforations in its lower portion for
5 the discharge of a cooling liquid, a tank within the cabinet for holding ice and receiving the liquid discharged from the radiator, and a pump connected to said tank and the lower radiator chamber, for pumping the cooled
10 liquid of the former to the latter.

In testimony whereof I affix my signature.

GLEN O'BRIEN.
